CLAIM

U.S. PATENT DOCUMENTS

I claim the ornamental design for a computer icon for a display panel, as shown and described.

DESCRIPTION

- D. 295,876 * 5/1988 Wells-Papanek et al. .
D. 341,848 * 11/1993 Bigelow et al. .
D. 398,001 * 9/1998 Bohnert et al. .
D. 404,727 * 1/1999 Hodges Wilsher et al. .
D. 418,123 * 12/1999 Koerner .
D. 422,990 * 4/2000 Bright et al. .

The single view is a front view of a computer icon for a display panel, the broken line drawing of a display panel and computer is for illustrative purposes only and forms no part of the claimed design.
